UNITED STATES PATENT OFFICE.

STEWART S. KURTZ, OF CANTON, OHIO, ASSIGNOR TO THE PAAR DOUBLE-CUSHION HORSE SHOE COMPANY, OF SAME PLACE.

DESIGN FOR A HORSESHOE-FRAME.

SPECIFICATION forming part of Design No. 33,090, dated August 14, 1900.

Application filed July 16, 1900. Serial No. 23,840. Term of patent 14 years.

To all whom it may concern:

Be it known that I, STEWART S. KURTZ, a citizen of the United States, residing at Canton, in the county of Stark and State of Ohio, have invented and produced a new and original Design for a Horseshoe-Frame, of which the following is a specification, reference being had to the accompanying drawings, forming part thereof.

- 5 o Figure 1 is a plan of a horseshoe-frame, showing my design. Fig. 2 is a side elevation thereof, and Fig. 3 is a section on the line 3 3 of either of the preceding figures looking toward the proximate end of the shoe.
- 5 o As shown in the drawings, the leading or material feature of my design consists of a horseshoe-shaped bar, which has substantially-parallel top and bottom surfaces, has its rear ends bent inward and forward into
- o **U** shape, and has on its under side, around

such **U**-shaped portions, at the outer edge thereof, a downwardly-extending flange.

Referring to the parts by letters, A represents the horseshoe-shaped bar, *a a* the **U**-shaped rear ends thereof, and *a' a'* the **U**-shaped flanges at the outer edges of these **U**-shaped ends. This flange on its outer surface merges with the outer surface of the bar A.

Having described my invention, what I claim as new, and desire to secure by Letters Patent, is—

The design for a horseshoe-frame substantially as herein shown and described.

In testimony whereof I hereunto affix my signature in the presence of two witnesses.

STEWART S. KURTZ.
